UNITED STATES PATENT OFFICE.

JOHN B. BETTEGAR, OF LOS ANGELES, CALIFORNIA.

FOLDING BED.

1,368,101.

Specification of Letters Patent.

Patented Feb. 8, 1921.

Application filed April 20, 1920. Serial No. 375,345.

To all whom it may concern:

Be it known that I, JOHN B. BETTEGAR, a citizen of the United States, residing at Los Angeles, in the county of Los Angeles and State of California, have invented new and useful Improvements in Folding Beds, of which the following is a specification.

This invention is a folding bed adapted, when open in position for use, to provide 10 a usual bed frame and arranged to be folded so as to have the appearance of a different article of furniture such as a buffet or side-board.

It is the object of the invention to provide 15 a construction of this character of few parts and which may be readily operated.

Further objects of the invention will be readily understood from the following description of the accompanying drawings in 20 which—

Figure 1 is a perspective view of the bed in folded position.

Fig. 2 is a similar view with the bed frame extended into position for use before the 25 mattress has been unfolded.

Fig. 3 is a similar view with the mattress partially unfolded.

Fig. 4 is a similar view with the mattress unfolded and the bed in position for use.

30 Fig. 5 is a horizontal section taken on the line 5—5 of Fig. 1.

Fig. 6 is a vertical section taken on the line 6—6 of Fig. 5.

Fig. 7 is a fragmentary section taken on 35 the line 7—7 of Fig. 4.

In the present embodiment of the invention I have shown the bed, when folded, arranged to have the appearance of a buffet or sideboard, although it will be obvious that 40 the bed may be arranged, when thus folded, to have the appearance of any desired article of furniture of the same general conformation.

The folding bed comprises a head member 45 forming the main portion of the buffet, a foot board forming the front of the body of the buffet, and side boards comprising pivotally connected sections arranged to be folded within the head board and engaged 50 at the respective ends of the side boards to the head member and to the foot member.

As an instance of this arrangement, the 55 head member may comprise a body consisting of a rear wall 1 and side walls 2; a top extending upwardly from the rear portion of the body thus formed and, preferably,

comprising a rear wall 3, side walls 4, a top 5, and a front 6. The upper end of the body portion of the buffet in front of the upwardly extending top is, preferably, closed 60 by a top surface 7 having hinged connections 8 with the upwardly extending top of the buffet, so that said top surface may be swung upwardly, as shown in Fig. 2, when the bed is extended into position for use. 65

The foot board of the bed consists of a panel 9, the outer surface of which may be formed to represent drawers or the like, this foot board being arranged, when folded, to close the front of the body portion of the 70 buffet. For this purpose recesses 10 may be provided at the front open side of the head board into which the foot board is moved when the bed is folded, the upper edge of the foot board being, preferably, provided 75 with a lip 11 over which the front edge 12 of the top surface 7 may be engaged when the bed is folded to retain the foot board in its folded position.

The hollow space within the head member 80 of the bed is adapted to receive the folded mattress and the folded side boards of the bed when the latter is in its folded position. As an instance of this arrangement the side boards of the bed may each 85 comprise sections 13 and 14 pivotally connected at their ends as by a hinge connection 15, this hinge being shown as a strap hinge and so arranged that the sections of the side board may be folded inwardly along 90 side one another with their outer surfaces adjacent one another. When the bed is unfolded the side boards thus formed are swung from their position along side one another to a position with their ends end to 95 end thereby providing the longitudinally extending side boards as shown in Fig. 2.

For this purpose the ends of the side boards, thus formed, are provided with 100 hinged connections with the head member and with the foot board of the bed respectively. These hinged connections are shown respectively at 16 and 17, the hinges, preferably, being usual strap hinges. The hinge 16 between the head member and the side board may be secured to the side wall 2 of the head member, and the hinge 17 at the opposite end of the side board is, preferably, secured to the rear surface of the foot board 9. 105

By the construction as thus described it will be seen that when the bed is in its 110

folded position the foot board 9 will close the front of the head member and the side boards will be received within the head member behind the foot board with the sections 5 of the respective side boards folded along side one another, and when it is desired to extend the bed into position for use the foot board may be drawn outwardly thereby unfolding the sections of the side boards until 10 they assume a position with the sections in longitudinal alignment thereby providing a usual bed frame. Suitable casters 18 may be provided upon the foot board, and the head member may also be provided with the usual 15 casters.

The mattress for the bed frame, thus provided, is arranged to be folded within the head member when the bed is in its folded position and is adapted to be unfolded on to 20 the bed frame when the bed is extended for use. The mattress may comprise the usual box mattress having the folding sections 19 and 20, each of these sections comprising a usual base frame 21 having the 25 upturned edges 22 and upon which the usual springs 23 are mounted, the springs being covered by the usual mattress 24 having its edges connected to the side edges 22 of the base frame. The sections 30 of the mattress are hinged together at their ends as by the hinges 25 having the respective straps thereof secured to the abutting ends of the respective base frames of the mattress sections, the parts being so arranged 35 that the hinged meeting edges of the mattress sections extend transversely of the bed frame with the mattress sections adapted to be folded one upon the other with their mattress surfaces adjacent one another.

40 The mattress is pivoted within the head member of the bed so that the head section of the mattress may be swung down upon the bed frame and the foot section of the mattress then swung down upon the bed 45 frame, the side boards of the latter, for this purpose, being provided with inwardly extending ledges 26 upon the respective sections thereof upon which the mattress is adapted to rest when in position for use 50 upon the bed frame. As an instance of this arrangement, the head section of the mattress is provided at its opposite sides with pivotal connections with the side boards of the head member, these pivotal connections 55 being, preferably, arranged approximately midway of the length of the head section of the mattress, so that the mattress sections, when folded upon one another, will be supported in vertical position within the head 60 member, as shown in Fig. 6. Each of the

pivotal connections for the head section of the mattress may comprise a bolt 27 extending through the side wall 2 of the head member and having a bracket 28 journaled thereon, said bracket having its end 29 extending 65 beneath the base frame of the head section of the mattress and suitably secured thereto.

By the arrangement, as thus described, it will be seen that when the bed is folded the mattress will have its sections folded one 70 upon the other and supported in vertical position within the head member of the bed, and the side boards of the bed frame will be folded with their sections one against the other within the head member of the bed in 75 front of the folded mattress, and the foot board of the bed will be folded within the front open end of the head member in front of the folded mattress and side boards to provide a front closure for the head member. The top surface 7 of the head member being lowered over the edge of the foot member, when thus folded, an article of furniture is provided completely disguising the true character of the bed. 85

When it is desired to use the bed as such, the top surface 7 being swung upwardly and the foot board 9 being drawn outwardly, the side boards will be extended to provide a usual bed frame upon which the sections of 90 the mattress may be unfolded.

Various changes may be made without departing from the spirit of the invention as claimed.

What is claimed is:

1. A folding bed comprising a head member forming a recess, a foot member, foldable side boards having hinged connections at their respective ends with the head member and the foot member, a mattress comprising head and foot sections arranged to be folded one upon the other, and pivotal connections between the respective sides of the head section of the mattress and said head member. 100

2. A folding bed comprising a head member, a foot member, hinged side boards pivotally connected to the head and foot members, and a folding mattress pivotally mounted on the head member. 105

3. A folding bed comprising a head member forming a recess, a foot member, hinged side boards pivotally connected to the head and foot members, and a folding mattress pivotally mounted in the recess of the head 115 member.

In testimony whereof I have signed my name to this specification.

JOHN B. BETTEGAR.
